RAIL-BRACE.

1,370,302.

Specification of Letters Patent.

Patented Mar. 1, 1921.

Application filed April 13, 1920. Serial No. 373,523.

To all whom it may concern:

Be it known that I, BENEDICT T. GIBBS, Jr., a citizen of the United States, residing at Chicago, in the county of Cook and State 5 of Illinois, have invented a certain new and useful Improvement in Rail-Braces, of which the following is a specification.

This invention relates to rail braces. The object of the invention is to provide a device 10 of this class for use against one side of a rail for adjustably laterally positioning it, and for rigidly securing it in position after wear has taken place between the rod and brace itself, and parts against which the 15 brace bears, the device being especially applicable to rails at and adjacent to switch points whose lateral movement to and from the unsupported side of the rail render the use of spikes or other securing devices impractical also on guard rails or on rails on 20 heavy curves.

The invention consists in a device of this class in which the rail brace block proper, moves only longitudinally of the base plate 25 on which it is usually mounted, thus insuring effective action of the device in all positions of adjustment, in such a device which can be easily and cheaply made, which is satisfactory in operation, and not readily liable to 30 get out of order, and particularly in many features and details of construction hereafter more fully set forth in the specification and claims.

Referring to the drawings in which similar numerals represent the same parts throughout the several views,—

Figure 1 is a plan view of mechanism illustrating this invention in its preferred form.

Fig. 2 is a sectional end view taken on the line 2—2 Fig. 1.

Like all devices of this class, the principal mechanism is carried by a horizontal base plate 10 extending under the rail 12 and adapted to be secured to the tie or other support by suitable mechanism, such for instance as spikes (not shown) inserted through the holes 14 provided for them. The upper surface of this plate 10 in the 45 design here shown, is provided with a recess of substantial depth having one wall 16 against which the edge 18 of one rail flange abuts, the bottom surface 20 on which all the essential parts of the device rest and an 50

opposite wall 22 against which bearing block 55 24 rests. This block 24 rises a substantial distance above the top of plate 10 to provide a vertical bearing face 26 extending across the plate 10 at substantially right angles thereto. Bearing block 24 is in the case here 60 illustrated made separable from the plate 10 and secured in place by suitable rivets 28, but these details are wholly unessential. Between rail 12 and face 26 of bearing block 24 are located two very essential members 65 entering in this invention, viz., a brace block 30 and a wedge 32, interfitting together on the angular line 34 which is diagonal to the center line of the rail 10 and to the bearing face 26. Brace block 30 is secured 70 against movement transversely of the plate 10 by two different mechanisms. The first, preferable, but not essential is the downwardly turned lips or flanges 36 embracing opposite side edges of the plate; the 75 second is the bolts 38 or the like extending rigidly upward from the plate 10 and entering elongated slots 40 formed in the member 30 so constructed as shown that when these bolts are loosened the block 30 can be 80 moved transversely of the rail and longitudinally of the plate 10, but not otherwise. These bolts 38 or the like, when tightened 85 perform the additional function of detachably securing the block 30 against movement in any direction.

In the particular case here illustrated, the bolts 38 are shown as having countersunk heads entering the bottom of the plate 10 with nuts and washers above the block 30, 90 but these are wholly unessential details, forming no part of the invention, as the bolts may be inserted and secured by any suitable means.

The block 30 on its under side, has an 95 angular surface 42 which bears against the upper surface of the right hand flange 44 of rail 12; between the block and the wedge 32 it has another inclined surface 46, which as shown, clears the surface 20 of 100 the plate 10, except at the extreme right hand end where there is a line contact 48 across the plate 10, with the result that when the nuts of bolts 38 are tightened the brace block 30 is rotated about this line or axis 105 48 in a counterclockwise direction to force the surface 42 of the block onto the rail flange 44 and thus clamp the rail to the plate

10 irrespective of the presence or absence of spikes or other securing devices adjacent to and over the left hand rail flange edge 18.

The lower half of the right hand edge of the 5 brace block 30 is cut away in the angular horizontal groove 50 within which a horizontally extending flange 52 of the wedge 32 fits with the result that when the brace block 30 is clamped down by the action of screws 10 38, described in the last paragraph, the wedge 32 is also clamped in fixed position. The smaller end of the wedge 32 is also provided with a top flange 54 extending over the adjacent portion of the brace block 30 15 and parallel to the flange 52. Through this flange 54 and the opposite portion of flange 52 are a row of registering holes 56 adapted to be selectively entered by cotter pin 58 adapted to be inserted, in the case here 20 illustrated, in the last hole beyond the edge 60 of plate 10 and the edge of brace block 30 after the wedge 32 has been driven upward as viewed in Fig. 1 to place to hold the wedge 32 in position even should the 25 bolts 38 move.

The plane of contact between the vertical face of member 52 which bears on the vertical face of groove 50 is inclined inwardly on member 52, as shown in Fig. 2, so that 30 when the parts are locked together in wedging action the bearing block cannot tilt upward from point 48 and get out from under the wedge.

In the operation of the device assume that 35 wear has taken place between the rail 12 and the plate 10 along the line 16 or wear has taken place between the brace itself and parts of the rail against which the brace bears and that adjustment has to be made.

40 The operator simply loosens the nuts on bolts 38 until it is possible by hitting the lower wedge 32 as viewed in Fig. 1 to drive said wedge upward, as viewed in Fig. 1, whatever distance may be required to move 45 both the block 30 and the rail 12 to the left as viewed in Fig. 2 to the desired position. On reaching this position the operator tightens the bolts 38 and inserts the cotter pin 58 in the last hole 54 which is beyond the edge 50 of plate 10 or brace block 30. In this position the rail is firmly clamped to the plate; the wedge is firmly clamped upon the plate, the wedge is held against retracting movement, even on the fastening produced by the bolt being loosened, and both 55 the wedge and block are in operating position directly over the plate 10, thus insuring a direct transfer of all strain upon the rail 12 directly to the bearing member 24 and consequently to the plate 10.

Having thus described my invention what I claim as new and desire to secure by Letters Patent, is:—

60 1. In mechanism of the class described, a 65 plate adapted to be secured upon a tie, pro-

vided with a bearing point for brace block mechanism located on one side of the rail; a brace block mechanism engaging the rail, a wedge having one face engaging the brace block in a plane angular to the central axis 70 of the rail, and a second face engaging the bearing point on the plate, means detachably securing said brace block to the plate preventing movement of the block transversely to the plate, while detachably permitting movement of the block longitudinally of the plate, means independent of the first mentioned securing means locking the wedge against transverse movement with reference to the plate, and means on the 80 block engaging the wedge to clamp it to the plate when the brace block is secured thereto.

2. In mechanism of the class described, a base plate adapted to be secured under a railroad rail, a rail, a brace block bearing against the rail, flanges on opposite sides of the block embracing the sides of the plate to permit movement of the block toward and from the rail and not otherwise, independent means for detachably securing the block to the plate, a wedge member having a face inclined to the length of the rail bearing on a corresponding face on the brace block and having another angular face parallel to the rail bearing on a supporting surface carried by the base plate and interfitting means between the wedge and brace block preventing movement of the wedge perpendicularly to the face of the plate independently of the brace block, and adjustable means for locking the wedge in selected positions of its lengthwise movement transversely of the base plate, parallel to the rail. 100

3. In mechanism of the class described, 105 a brace block for movement to and from a rail, a wedge for movement transversely of the brace block there being a pair of spaced flanges on the wedge interfitting a flange on the brace block, the flanges on the wedge being provided with perforations adapted to be selectively used by a cotter pin through successive pairs of holes as they are beyond an edge of the brace block, for the purposes set forth.

4. In mechanism of the class described, a 110 plate adapted to be secured upon a tie, provided with a bearing point for brace block mechanism located on one side of the rail; a brace block engaging the rail, a wedge having one face engaging the brace block in a plane angular to the central axis of the rail, and a second face engaging the bearing point on the plate, the contact face between the block and wedge being inclined downwardly 115 in the body of the wedge and outwardly from the body of the block, means detachably securing said brace block to the plate preventing movement of the block transversely to the plate, while detachably per- 120 125 130

- mitting movement of the block longitudinally of the plate, and independent means locking the wedge against transverse movement with reference to the plate.
- 5 5. In mechanism of the class described, a plate adapted to be secured upon a tie, provided with a bearing point for brace block mechanism located on one side of the rail; a brace block engaging the rail, a wedge
- 10 having one face engaging the brace block in a plane angular to the central axis of the rail and a second face engaging the bearing point on the plate, the contact face between the block and wedge being inclined
- 15 downwardly in the body of the wedge and outwardly from the body of the block, means detachably securing said brace block to the plate preventing movement of the block transversely to the plate, while detachably permitting movement of the block 20 longitudinally of the plate, independent means locking the wedge against transverse movement with reference to the plate, and means on the block engaging the wedge to clamp it to the plate when the brace block 25 is secured thereto.

In witness whereof, I have hereunto subscribed my name in the presence of two witnesses.
